UNITED STATES PATENT OFFICE

GEORGE SUBICK, OF CHICAGO, ILLINOIS

SUPPORTING AND DISPLAY RACK

Application filed September 12, 1930. Serial No. 481,503.

This invention relates to certain novel improvements in supporting and display racks, and has for its principal object the provision of an improved construction of this character which will be highly efficient in use and economical in manufacture.

Among the several objects of this invention is the provision of an improved construction in a supporting rack among the several objects of which is to display thereon in an improved manner such articles as neck ties, etc.

Another object of the invention is the provision of an improved display rack embodying a plurality of rotatable arms which are adapted to display, among other articles, neck ties in a manner such that each arm may be moved independently of the others so as to permit viewing of the merchandise, such as neck ties, thereon, without necessitating the movement of the other supporting arms.

A further object of the invention is the provision of an improved supporting and display rack which may be detachably mounted on a vertical wall, or on a horizontally extending pole or rod, or suspended freely from a line, hook, or other supporting element.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view depicting a preferred form of construction of the invention and showing one manner of detachably mounting the invention, in this instance on a vertical wall;

Fig. 2 is a vertical sectional view of the invention as depicted in Fig. 1;

Fig. 3 is a rear plan view partly in section of the invention taken substantially on the line 3—3 in Fig. 2, but depicting the device mounted on a horizontal support, in this instance a cylindrical rod;

Fig. 4 is a sectional view substantially on the line 4—4 on Fig. 3, depicting a preferred

manner of mounting the rotatable arms of the rack on the supporting shaft;

Fig. 5 is a perspective view of a modified form of construction of the rotatable rack arms; and

Fig. 6 is a perspective view of another modified form of construction of the rotatable rack arms.

Referring to the drawing wherein the preferred embodiments of the invention are illustrated, and more particularly now to Figs. 1 to 4 inclusive, indicated at 10 is a plurality of supporting arms which are rotatably mounted on a shaft 11 by means of cylindrical portions 12 which are wrapped around the shaft 11 so as to float thereon. The arms 10 include upstanding end portions 13 so that articles of merchandise, such as neck ties, may be supported and retained on these arms for display purposes.

The lower end of the shaft 11 is threaded, as indicated at 14, and a suitable retaining nut 15 is threaded thereon. The upper end portion 16 of the shaft 11 projects through the bight portion 17 of a substantially U-shaped bracket generically indicated at 18. As shown in Figs. 1 and 2, the end portion 16 of the shaft 11 likewise projects through the base 19 of a combination hook and bracket element generically indicated at 20. The hook and bracket element 20 includes a hook 21 which provides a stem portion 22 and, as shown in Fig. 2, the upper end portion 16 of the shaft 11 is secured to this stem portion 22 in any suitable manner such as by soldering, as indicated at 23.

The hook and bracket element 20 includes the base portion 19 of a substantially L-shaped bracket generically indicated at 24, and the base portion 19 is integral with the stem portion 25 of the bracket. The stem portion 25 of the L-shaped bracket is secured to the hook 21 in any suitable manner such as by soldering, as indicated at 26. There is provided in the stem portion 25 of the bracket 24 a plurality of bayonet slots 27. As shown in Figs. 1 and 2, one manner of mounting the invention is by engagement of the bayonet slots 27 with screws such as 28 which are so mounted in a suitable vertical

- support 29 that the head portions thereof project outwardly from the support 29 which may be any vertical structure such, for example, as a wall. It is apparent, therefore, that my improved display device may be quickly and conveniently detachably mounted on a vertical support and it will be seen that, when so mounted, the arms 10 may be individually rotated so that in order to view or examine an article such, for example, as a neck tie displayed on one of the arms 10, it is not necessary to move the other arms 10 since these arms are rotatable independently of each other.
- As shown in Figs. 1 and 3, the U-shaped bracket 18 includes arms 30 and 31 which are hingedly connected to the bight portion 17 by means of suitable hinge structures 32 and 33. There is provided on the inner side of the arm 30, as shown in Fig. 3, an ear 34 to which is attached one end of a coil spring 35. A similar ear 36 is provided on the arm 31 and the other end of the coil spring 35 is attached to this ear 36. The upper end of the arm 30 is concavely arcuate in contour and sharpened to provide a knife edge 37, and the upper end of the arm 31 is similarly constructed to provide a knife edge 38. It will be seen, therefore, as diagrammatically illustrated in Figs. 2 and 3, that my improved display rack may be detachably mounted on a horizontally extending pole or rod such as 39. In mounting the invention in this manner no vertical wall support is required and hence the bayonet slots 27 are not used in this case. In this manner of mounting the invention, the hook 21 is suspended from the pole 39 and the arms 30 and 31 are extended into the dotted line position of Fig. 3 so that the knife edges 37 and 38 engage the pole 39. Manifestly, therefore, when the hook 21 is lifted off the pole 39 the arms 30 and 31 are folded in toward each other by the tension of the spring 35. Obviously, however, the display rack may be suspended loosely from any horizontal support over which the hook 21 may be fitted without employing the arms 30 and 31.
- In Fig. 5 a modified form of construction for the rack arms is depicted, and in this instance there is provided a substantially U-shaped bracket generically indicated at 40 and which includes a bight portion 40' and arms 41 and 42 which are bent to provide loops 43 and 44 that are adapted to be rotatably mounted on the shaft 11. The loop 43 is integral with a fixed arm 45 which is upturned at its outer end as indicated at 46. The upturned portion 46 is integral with a portion 47, and this portion 47 is formed unitarily with a movable arm 48 at the end of which is provided a loop 49 which is slidably mounted on the bight portion 40' of the U-shaped bracket 40.
- In Fig. 6 another modified form of con-
- struction for the rack arms is depicted. In this instance I provide a cylindrical metal tube 50 which is preferably of non-rusting material and in which is provided a bore 51 that is adapted to receive the shaft 11. Secured to the tube 50 in any suitable manner, such as by soldering, is an arm 52 at the end of which is provided an upturned portion 53. Likewise secured to the tube 50 in any suitable manner, such as by soldering, and adjacent the upper end thereof is an arm 54 at the outer end of which is provided the upturned portion 55. Adhesively secured to the tube 50 on the upper end portion thereof is a section of rubber tubing 56, and loosely mounted on the arm 54 and upturned portion 55 is a section of rubber tubing 57. The sections of rubber tubing 56 and 57 are adapted to keep the neck ties or other articles of merchandise on display from contact with the metallic portions of the arm as depicted in Fig. 6; it being understood that the constructions in Figs. 1 to 5 inclusive are preferably of non-rusting material. In this connection the arms 10 are preferably though not necessarily made of aluminum.
- From the foregoing description of my invention, it is manifest that I have provided an improved display rack which while being simple in construction is highly efficient in use and economical in manufacture, while permitting individual movement of each of the rotatable arms and consequently individual and effective display of articles of merchandise displayed on each of the arms.
- While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.
- Having thus described my invention, what I claim as new and desire to protect by Letters Patent is:
- A device of the class described, comprising a bracket structure including a hook for supporting the device from a support, arms hinged to said bracket structure, having knife edges, and adapted to be spread apart and engage said support, and a resilient member for normally retaining said arms in collapsed position on opposite sides of said hook.
- In testimony whereof I affix my signature.
- GEORGE SUBICK.
